H. F. ROACH,
INSULATION FOR RAIL JOINTS,
APPLICATION FILED JAN. 11, 1917.

1,258,251.

Patented Mar. 5, 1918.

Inventor,
Harry F. Roach.
By Oakwell & Chenebattys.

UNITED STATES PATENT OFFICE.

HARRY F. ROACH, OF ST. LOUIS, MISSOURI.

INSULATION FOR RAIL-JOINTS.

1,258,251.

Specification of Letters Patent.

Patented Mar. 5, 1918.

Original application filed January 11, 1917, Serial No. 141,821. Divided and this application filed January 11, 1917. Serial No. 141,822.

To all whom it may concern:

Be it known that I, HARRY F. ROACH, a citizen of the United States, residing at St. Louis, Missouri, have invented a certain 5 new and useful Improvement in Insulations for Rail-Joints, of which the following is a full, clear, and exact description, such as will enable others skilled in the art to which it appertains to make and use the same.

10 This invention relates to insulated rail joints,—and particularly to the insulation used in the rail joint described in my pending application Serial No. 141,821, filed January 11, 1917.

15 One object of my present invention is to provide a sole plate or base plate insulating member for rail joints, which is so designed that when it is in operative position portions on the same coöperate with one of the 20 side members of the joint and with the base plate of the joint to prevent said sole plate from shifting into an improper position.

Another object is to provide insulating members for the side portions of a rail joint 25 which are so constructed that the rails positioned in the joint can expand and contract without causing said insulating members to be cracked or broken by the bolts which extend transversely through the rails 30 and through the side members of the joint.

Figure 1 of the drawings is a side elevational view, partly broken away, of a rail joint equipped with insulating members constructed in accordance with my invention.

35 Fig. 2 is a vertical cross-sectional view of said joint.

Fig. 3 is a perspective view of the sole plate.

Fig. 4 is a perspective view of one of the 40 bolt insulating members; and

Fig. 5 is a perspective view, illustrating the two side insulating members that insulate the rails from the side portions of the joint.

45 Referring to the drawings, which illustrate the preferred form of my invention, A designates a metal member that is provided with a base plate 1 that supports the rails and with a side portion 2 that extends longitudinally along one side of the rails. A member B that is arranged on the opposite side of the rails coöperates with the member A to hold the rails in longitudinal alinement with each other, and bolts or other suitable fastening devices 3 pass transversely

through the members A and B and through the webs of the rails, so as to hold said elements in operative position with relation to each other.

A sole plate or base plate C of insulating material is arranged between the base plate 1 and the base flanges of the rails, and two side insulating members D and D' are arranged between the rails and the portions 2 and B of the joint that extend longitudinally of the rails at the sides of the same. The sole plate C is provided at one of its side edges with an upwardly-projecting flange 4 that projects into a pocket in the member A which is provided with end walls 5 that coöperate with the ends of the flange 4 on the sole plate to prevent said sole plate from creeping or moving longitudinally of the joint. The sole plate C is also provided at its ends with downwardly-projecting flanges 6 that lap over the ends of the base plate 1, as shown in Fig. 1, and thus prevent the sole plate from assuming an angular position on the base plate. It is immaterial how the pocket in the member A is formed, 80 but when the joint comprises a member A having a portion 7 that laps over the base flanges of the rails, as shown in Fig. 2, so as to prevent the ends of the rails from moving upwardly off a flat rail supporting surface 85 8 at the center of the base plate, as described in my pending application previously referred to, said pocket can be formed by said overlapping portion 7 and by lugs 5 at the ends of the same that constitute the end 90 walls of the pocket.

The side insulating members D and D' are so formed that they prevent any parts of the members A and B from contacting with the rails, the abutting ends of said rails being separated by the usual insulating end post (not shown). A vertically-disposed portion 9 of each of said members which is positioned opposite the webs of the rails is provided with elongated bolt openings 10 through which the bolts 3 pass, said bolt openings 10 being long enough so that the rails can expand and contract without causing the bolts 3 to exert pressure on the members D and D', and thus possibly break 100 or crack said members. The bolts 3 are insulated from the members A and B of the joint by means of tubular-shaped insulating devices 11 arranged in the bolt holes in the members A and B and provided at their 110

outer ends with laterally-projecting flanges or head portions 11^a that insulate the heads and nuts on the bolts from the members A and B.

Having thus described my invention, what I claim, and desire to secure by Letters Patent, is:

1. An insulating member for rail joints consisting of a sole plate provided at one edge with an upwardly-projecting flange which is adapted to coöperate with a means on the joint that prevents the sole plate from

moving longitudinally of the joint, and downwardly-projecting flanges at the ends of said sole plate that lap over the ends of the base plate on which the sole plate rests.

2. An insulating member for rail joints, consisting of a sole plate provided at one edge with an upwardly-projecting flange which is adapted to coöperate with a means on the joint that prevents the sole plate from moving longitudinally of the joint.

HARRY F. ROACH
